UNITED STATES PATENT OFFICE.

JOHN B. HADAWAY, OF BROCKTON, MASSACHUSETTS.

SHOE-SEWING MACHINE.

No. 838,183.

Specification of Letters Patent.

Patented Dec. 11, 1906.

Application filed May 9, 1904. Serial No. 207,006.

To all whom it may concern:

Be it known that I, JOHN B. HADAWAY, a citizen of the United States, residing at Brockton, in the county of Plymouth and 5 State of Massachusetts, have invented certain new and useful Improvements in Shoe-Sewing Machines; and I do hereby declare the following to be a full, clear, and exact description of the invention, such as will enable 10 others skilled in the art to which it appertains to make and use the same.

This invention relates to shoe-sewing machines having means for separating or indenting the stitches during the operation of sewing 15 the sole of a shoe to the welt.

In an application filed by me January 16, 1904, Serial No. 189,249, it was proposed to provide mechanism for throwing the stitch-separating means out of operation during the 20 continued operation of the machine, so that in sewing a shoe the seam at the shank portion should, if desired, be left unseparated or unindented, while the seam at the fore part should be indented or separated.

25 In sewing the sole of a shoe it is usual to lengthen the stitches in the shank; and the object of the present invention is to provide a machine of the character above described with means operating simultaneously to 30 throw the stitch-separating mechanism out of operation and to lengthen the stitches, so that a single operation only may be necessary in order to change the length of the stitches and to throw the indenting mechanism into or out of operation.

To this end the invention consists in the sewing-machine hereinafter described, and particularly defined in the claim.

The invention is applicable to different 40 forms of sewing-machines irrespective of the nature of the stitches formed or the form or mode of operation of the sewing instrumentalities, and it may be embodied in a fair-stitch machine, as well as in an outsole-stitching machine.

The invention as illustrated in the drawings is embodied as an improvement in the machine described and shown in Letters Patent of the United States No. 616,314, granted 50 to me December 20, 1898.

In the drawings, Figure 1 is a front elevation of a portion of a sewing-machine embodying the present invention. Fig. 2 is a plan of the same, and Fig. 3 is a right-hand 55 side elevation.

With the exception of the means for throwing the stitch-separating device into and out of operation the illustrated embodiment of the present invention is constructed like that of the above-mentioned Letters Patent. 60 The stitch-forming mechanism is, as in the said patent, substantially like that shown and described in United States Patent No. 473,870, issued to the Goodyear Shoe Machinery Company as assignee of Z. T. French 65 and William C. Meyer, dated April 26, 1892, to which patent reference may be had for information concerning the parts of the machine not shown in the accompanying drawings. 70

The sewing instrumentalities shown in the drawings comprise the needle 1, the awl 2, the work-support 3, and the presser-foot 4, all constructed and operating as in the said Patent No. 473,870, with the exception of 75 the modification of the presser-foot mechanism described in the said patent No. 616,314.

The needle is carried by a segment 5, loosely mounted on a stud 6, projecting from the horizontal portion 7 of the frame of the 80 machine. The awl is carried by a segment 8, loosely mounted on a stud 9, carried by the standard 10, rising from the feed-slide 11. The presser-foot is secured to a lever 12, pivoted on the stud 13, secured to a part 14 of the 85 frame of the machine.

The stitch-separating mechanism in its general construction and mode of operation is substantially identical with the stitch-separating mechanism illustrated and described 90 in the said Patent No. 616,314. It is provided, however, with means for throwing it into and out of operation, and these means are interconnected with the means for changing the feed to lengthen the stitches. The 95 stitch-separating tool 23 is actuated, as in said patent, by mechanism comprising a cam-lever 29, carrying a roll 31, which bears against the periphery of a cam 32 on the main shaft 33 of the sewing-machine. The 100 cam-lever 29 is fulcrumed on a stud 30, which is mounted to slide in an elongated hole 35 in the frame of the machine. A lever 40, pivoted at 41 on the frame, is provided with a slot 42, which is curved eccentrically with 105 the fulcrum 41 and which embraces the stud 30. When the lever is in the position of the drawings, the stitch-separating mechanism is operative; but when the lever is drawn back the curved slot 42 draws the stud 30 upward 110

the curved slot 42 draws the stud 30 upward 110

in the hole 35, thereby raising the cam-roll 31 from the cam and causing the operation of the stitch-separating mechanism to cease.

The feeding and feed-regulating means consist of the awl 2, the awl-segment 8, the feed-slide 11, and the feed-regulating lever 50, which latter is provided with a pin carrying a slide-block in operative engagement with the arc-shaped slot in the under side of the feed-lever 51. The feed-regulating lever 50 is actuated by a hand-lever 53, which is provided with a tapered adjustable block 54, which is located in a tapered opening between two projections on the feed-regulating lever 50. By adjusting the block 54 back and forth on the hand-lever 53 more or less lost motion may be provided between the hand-lever and the feed-regulating lever. The hand-lever 53 is provided with a downwardly-extended portion which carries a pivoted pin 55, which receives through a hole in its head a rod 56. This rod carries split collars 57, which are adapted to engage the opposite sides of the head of the pin 55. The rod 56 is connected to a lever 58, pivoted at 59 to a small bracket 60, which is secured upon the lever-shaft 61 in the rear of the machine. The upper end of the lever 58 is connected by a link 62 with the lever 40. The above-described arrangement is such that when the hand-lever 53 is moved forward to lengthen the feed upon reaching the shank the stitch-separating mechanism is thrown out of operation through the connecting devices described, so that the simultaneous lengthening of the stitch and throwing out of the stitch-separating mechanism is secured. Owing to the variations in the length of stitches which may be employed in the different qualities of work, the lost-motion construction between the hand-lever 53 and the feed-regulating lever 50 is provided, so that a considerable variation in the length of the stitches may be secured with a constant throw of the hand-lever 53.

In ordinary use the stitcher provided with the present mechanism will be operated in the following manner: The hand-lever 53

being in its forward position to cause the feed mechanism to feed the work the proper distance for the formation of the long stitches along the shank and the hand-lever 40 being in its rear position holding the stitch-separating devices out of operation, the sewing of the shoe will be begun near the heel on the inside (or outside) of the shank of the shoe, and the sewing along the shank will be continued, the stitch-separating mechanism being inoperative until the shank is completed, when the hand-lever 53 will be moved rearwardly to shorten the stitches, this movement simultaneously throwing the stitch-separating mechanism into operation by the means described. Then the sewing around the fore part of the shoe will be continued, with the stitch-separating mechanism operating to separate and indent the intervals between the stitches upon this part of the shoe until the opposite side of the shank near the ball is reached, when the lever 53 will again be drawn forward to lengthen the stitches and to throw the stitch-separating mechanism out of operation. The sewing of the other side of the shank of the shoe will then be completed by an unindented seam. When the operator takes up the next shoe, he begins sewing with the parts in the position in which he lift off sewing the previous shoe, and the operations recited are repeated.

Having thus described the invention, what is claimed is—

A shoe-sewing machine, having, in combination, stitch-forming mechanism, feeding means, feed-regulating means, stitch-separating mechanism, and connected means for throwing the stitch-separating mechanism into and out of operation and operating the feed-regulating means, substantially as described.

In testimony whereof I affix my signature in presence of two witnesses.

JOHN B. HADAWAY.
